US0D1006523S

(12) **United States Design Patent** (10) Patent No.: **US D1,006,523 S**
(45) Date of Patent: ** Dec. 5, 2023

(54) **COOKING OVEN**

(71) Applicant: **MIDEA GROUP CO., LTD.**, Foshan (CN)

(72) Inventor: **Bingcan Liang**, Guangdong (CN)

(73) Assignee: **MIDEA GROUP CO., LTD.**, Guangdong (CN)

(**) Term: **15 Years**

(21) Appl. No.: **35/514,099**

(22) Filed: **Dec. 7, 2021**

(80) **Hague Agreement Data**

Int. Filing Date: **Dec. 7, 2021**

Int. Reg. No.: **DM/220171**

Int. Reg. Date: **Dec. 7, 2021**

Int. Reg. Pub. Date: **Apr. 22, 2022**

(30) **Foreign Application Priority Data**

Aug. 26, 2021 (CN) 202130560078.X

(51) **LOC (14) Cl.** **07-02**

(52) **U.S. Cl.**

USPC **D7/350.1**
